UNITED STATES PATENT OFFICE.

WILLIAM FITZ CHARLES MASON MCCARTY, OF ST. PETERSBURG, RUSSIA,
ASSIGNOR OF ONE-HALF TO HENRY LEVIS, OF PHILADELPHIA, PA.

APPARATUS FOR THE MANUFACTURE OF HYDROCARBON GAS.

SPECIFICATION forming part of Letters Patent No. 296,201, dated April 1, 1884.

Application filed December 21, 1883. (No model.)

To all whom it may concern:

Be it known that I, WILLIAM F. C. M. MCCARTY, a citizen of the United States of America, at present residing at St. Petersburg, Russia, have invented a new and useful Apparatus for the Manufacture of Hydrocarbon Gas, of which the following is a specification.

The object of my invention is to provide an apparatus by which an illuminating-gas pure and free from oxygen and carbonic-oxide gas may be obtained.

My invention consists in the devices and apparatus hereinafter described and claimed.

In the drawings, Figure 1 is a view partly in section and partly in elevation. Fig. 2 is a sectional elevation of the apparatus shown in Fig. 1. Fig. 3 is central sectional view through the furnace B and combustion-flue B' of Fig. 1, and Fig. 4 is a detailed sectional view of the injecting device, by means of which the hydrogen gas and liquid hydrocarbon are introduced to the mixing-chamber I of Fig. 1.

The same letters of reference refer to similar parts wherever used.

B, D, and E are furnaces containing muffles C, F, and G. The construction of these three furnaces is similar, and may be understood by reference to Fig. 3, in which B represents the masonry of the furnace; C, a muffle of boiler-iron, which is provided with shelves *a b c*, and with induction and eduction pipes *d* and *e*.

f is the grate-bar, and *B'* the combustion-flue. The combustion-flues *B'*, *D'*, and *C'* are respectively provided with dampers *B''*, *D''*, *E''*.

A is a steam-boiler or superheater of any suitable construction, provided with an eduction-pipe, *d*, opening into the muffle *C*.

e is a pipe leading from the top of the muffle *C* to the bottom of the muffle *F*, and *k* is a pipe leading from the top of the muffle *F* to the bottom of the muffle *G*.

l is a pipe leading from the top of the muffle *G* and opening into a mixing-chamber, *I*. The pipe *l* at its discharge end *m* is enlarged, and within this enlargement is introduced the discharge end of the pipe *n*, which leads from the hydrocarbon-holder *H*, the construction being such that the passage of the hydrogen

gas through the pipe and around the discharge end of the pipe *n* causes the ejection of the fluid hydrocarbon supplied from the tank or vessel *H* into the mixing-chamber *I* in a spray or finely-divided condition.

K is a coil leading from the mixing-chamber *H* upwardly through a stack or flue of masonry, and thence by a pipe, *K'*, downwardly into a second flue or stack having as a continuation of said pipe *K'* a second coil, *K''*. The latter coil, by means of the pipe *K'''*, is caused to discharge into the bottom of a washer, *L*, set in proper brick-work, and provided with a grate or fire-box, *M*. The washer *L* is provided with two circulating-pipes, *N'* and *N''*, the lower open extremities of each of which reach nearly but not quite to the bottom of said vessel, the upper extremities being bent over and provided with rose ends or openings.

M' and *M''* are perforated diaphragms or sieves.

O is a gas-discharge opening, and *Q* is an opening for the discharge of the products of combustion from the fire-box *M*.

P P' are pipes extending into the washer *L*, and having their open ends therein nearly but not quite in contact with the lower interior end of said chamber, the outer ends of said pipes being provided with suitable valves for closing the same. The shelves *a b c* are provided with calcium protoxide, (lime,) and the muffle *F* is upon its shelves provided with iron, copper, or other easily-oxidizable metal in a finely-divided condition, while the muffle *G* is upon its shelves provided with beds of charcoal. The materials are fed to said muffles by removing the plates from the front ends thereof, and the luting by which they are held in place, after which the plates are replaced and luted in position. The muffles *C* and *F*, with their contents, are heated by means of fire upon the grate-bars *f* and *g* in the combustion-chambers *B* and *D*, respectively.

I may here remark that the muffle of the furnace *B* may be charged with finely-divided iron or copper, and the muffle in the furnace *D* with lime, without changing the nature of my invention. Steam is fed from the superheater or boiler *A*, through the pipe *d*, to the

bottom of the muffle C, and passes backward and forward over and through the lime contained upon the shelves of said muffle, whereby oxygen and such carbonic acid as may be present in said steam are to a large extent absorbed and removed therefrom. The hydrogen resulting, with such impurities as it may contain, is then conveyed by the pipe e to the bottom of the muffle F, where it is discharged, and passes over and through the heated finely-divided iron or copper or equivalent material contained upon the shelves thereof, by which said gas is further purified from oxygen and carbonic-oxide gas. This purified gas is then, by means of the pipe k, conveyed to the lower part of the muffle G, at which point it is discharged in said muffle and passes over and through the bed of charcoal contained upon the shelves thereof, whereby its complete purification from oxygen and carbonic-oxide gas is insured. The purified and highly-heated hydrogen so obtained is then conveyed by the pipe l to the mixing-chamber I, and in its escape through the enlarged orifice m of the pipe l into said chamber causes the stream of liquid hydrocarbon fed by the pipe n from the holder H to be forced into said mixing-chamber I in a finely-divided condition or spray. This mixture of hydrocarbon and hydrogen gases then passes through the coil K, which has been highly heated by fire upon the grate-bars J, whereby said gases become more or less fixed. From the coil K, through the pipe K', this gas may be conveyed to a second coil, K'', heated by fire from the grate J', whereby a perfect fixing of the gas may be insured. The fixed gas so obtained is then conveyed through the pipe K'' to the washer L, and discharged into said chamber at the bottom thereof, said chamber having previously been supplied with hydrate of lime, ammonia, and water, or other suitable cleansing solution, the passage through which of said gas purifies the same and fits it for use, the purified gas being removed from said washer to a suitable storage-reservoir through the orifice O. The hydrocarbon gas introduced to the purifier L through the pipe K'' is caused to come into more thorough contact with the cleansing solution in said chamber by reason of the fact that the heat arising from the fire-box M causes a circulation of the bath in the washer L upwardly through the pipes N' N'', and a discharge of said mixture through the rose discharges on the upper ends of said pipes, respectively, and a consequent trickling of said solution downwardly through the perforated diaphragms M' and M'', by which the upward current of gas comes intimately into contact with said purifying mixture. The pipes P and P' may be used to free the purifier L of its contents, pressure applied to one of these pipes causing the contents of said purifier to be ejected through the other.

B² and D² are flues connecting the combustion-chambers of the furnaces B and D and D 65 and E, respectively, said flues being provided with dampers. This construction enables the retort of the combustion-chamber E to be heated by causing the currents of heat and the products of combustion from the furnaces B 70 and D to pass through the furnace E and be discharged through the smoke-stack E', whereby the charcoal of the muffle G may by heat be purified of its oxygen and carbonic oxide, when such purification becomes necessary, instead of removing said charcoal from said muffle, and replacing it by fresh supplies thereof. 75

Having thus described my invention, I claim—

1. In an apparatus for the manufacture of 80 hydrocarbon gas, in combination, three or more furnaces, the combustion-chamber of each being provided with a closed muffle containing, respectively, lime, iron, (or copper in a finely-divided state,) and charcoal, a mixing-chamber provided with a hydrocarbon-injector, and a heating or fixing coil or chamber, the arrangement being such that superheated steam introduced to the first-named muffle may pass over or through the heated lime therein, 90 and thence over or through the heated iron or copper in the second muffle, and thence over or through the charcoal in the third muffle, and thence into the mixing-chamber and become mixed with the hydrocarbon therein, and thence into or through the heating or fixing coil or chamber, as specified. 95

2. In an apparatus for the manufacture of hydrocarbon gas, in combination, a steam boiler or superheater, A, furnaces B, D, and E, provided, respectively, with muffles C, F, and G, said superheater and muffles being connected by pipes d, e, and k, respectively, a mixing-chamber, I, provided with a hydrocarbon-supply tube, n, and with a hydrogen-gas-supply tube, l, leading from the muffle G, and a fixing chamber or coil, K, as specified. 105

3. In an apparatus for the manufacture of hydrocarbon gas, in combination, a steam boiler or superheater, A, furnaces B, D, and E, provided, respectively, with muffles C, F, and G, said superheater and muffles being connected by pipes d, e, and k, respectively, a mixing-chamber, I, provided with a hydrocarbon-supply tube, n, and with a hydrogen-gas-supply tube, l, leading from the muffle G, one or more fixing chambers or coils, K, and a washer, L, as specified. 110 115

In testimony whereof I have hereunto signed my name this 11th day of December, A. D. 120 1883.

WILLIAM FITZ CHARLES MASON McCARTY.

In presence of—

W. C. STRAWBRIDGE,
J. BONSALL TAYLOR.
